(57) CLAIM

The ornamental design for a plush toy, as shown and described.

DESCRIPTION

FIG. 1 is a front perspective view of a plush toy according to my new design.

FIG. 2 is a side view of the plush toy of FIG. 1.

FIG. 3 is a top view of the plush toy of FIGS. 1 and 2; and, FIG. 4 is a rear view of the plush toy of FIGS. 1-3.

The design of the present invention and as shown in FIGS. 1-4 is a plush toy, comprised of a body in the general shape of a computer monitor, with unproportional caricature legs and arms protruding from the computer monitor.
